(57) **CLAIM**

The ornamental design for a lid for a pan, as shown and described.

DESCRIPTION

FIG. 1 is a top front left side perspective view a lid for a pan showing our new design;

FIG. 2 is a left side view thereof;

FIG. 3 is a right side view thereof;

FIG. 4 is a front view thereof;

FIG. 5 is a rear side view thereof;

FIG. 6 is a top plan view thereof;

FIG. 7 is a bottom plan view thereof;

FIG. 8 is a bottom perspective view thereof;

FIG. 9 is an enlarged top front left side perspective view of the detail identified in FIG. 1;

FIG. 10 is an enlarged left side view of the detail identified in FIG. 2;

FIG. 11 is an enlarged right side view of the detail identified in FIG. 4;

FIG. 12 is an enlarged top plan view of the detail identified in FIG. 6;

FIG. 13 is an enlarged bottom plan view of the detail identified in FIG. 7; and,

FIG. 14 is an enlarged bottom perspective view of the detail identified in FIG. 8.

The evenly-spaced broken lines in the figures represent unclaimed subject matter only and form no part of the claimed design. The dash-dot-dash broken lines immediately adjacent to the shaded area represent unclaimed boundaries of the design.

1 Claim, 8 Drawing Sheets
